ROTARY DUPLICATOR

Clifford N. Johnson, Chicago, Ill., assignor to
Ditto, Incorporated, Chicago, Ill., a corpora-
tion of West Virginia

Application February 11, 1932, Serial No. 592,242

4 Claims. (Cl. 101—132)

The invention relates to rotary duplicators and particularly to a rotary duplicator having a rotating drum provided with a duplicating surface for receiving an impression from a master sheet and for imparting the same to blank sheets subsequently impressed on the surface.

One of the objects of the invention is to provide a rotary type of duplicator with feeding means functioning to contact a top sheet of the 10 paper stock supported thereon with the duplicating surface on the drum, the sheet adhering to the surface whereby rotations of the drum separate the top sheet from the remaining sheets and presents the same to an impression roller.

15 A more specific object of the invention is to provide a movable paper tray having operative connection with a cam on the rotating drum by means of which an end of the tray adjacent thereto is caused to oscillate in timed relation with 20 the rotations of the drum, the oscillations contacting the marginal edge of the top sheet of the stock on the tray with the leading edge of the duplicating surface for the purpose of adhering the sheet to the surface.

25 A further object resides in the provision of an impression roller pivotally mounted in the frames of the machine and being resiliently urged into contact with the duplicating surface, the construction maintaining uniform the pressure exerted upon the surface by the roller.

30 A further object is to provide novel stripping mechanism including a pair of stripping rollers and a co-operating member oscillating in timed relation with the rotations of the drum to direct 35 the leading edge of the impressed sheet between said rollers.

35 A further object is to provide means actuated by the drum for oscillating the co-operating member, which will be simple in construction 40 and positive in operation.

With these and various other objects in view, the invention may consist of certain novel features of construction and operation as will be more fully described and particularly pointed out 45 in the specification, drawings and claims appended hereto.

In the drawings which illustrate an embodiment of the device and wherein like reference characters are used to designate like parts—

50 Figure 1 is a side elevational view of the complete machine constructed in accordance with the present invention;

Figure 2 is a top plan view, parts of the cylinder being broken away to show the tightening means for the gelatin band;

Figure 3 is a vertical sectional view taken substantially through the center of the cylinder with the parts in position as shown in Figure 1;

Figure 4 is a vertical sectional view taken substantially on the plane indicated by the line 4—4 of Figure 3;

Figure 5 is an enlarged fragmentary sectional view showing the position of the parts in advance of directing the leading edge of the impressed sheet between the stripping rollers, and

Figure 6 is an enlarged fragmentary sectional view showing the position of the parts at the end of a duplicating operation.

The machine is mounted within spaced frame members 10 and 11, Figures 2 and 3, held in spaced relation by means of an upper tie rod 12, a supporting member 13 extending from frame to frame at substantially the central portions and being secured thereto by fastening screws 14 and by means of a hollow base member indicated 70 in its entirety by 16 upon which the frames are suitably supported. The base includes a top plate member 17, a bottom plate member 18 and side members 19 and an end member 20, respectively, the other end member 21 having a handle 22 secured thereto and projecting from one face of the same, and a receptacle 23 projecting from the other face, the latter being received within the hollow base and riding upon base angle plates 24. Upper angle plates 25 form guides serving 75 to correctly position the receptacle within the base. The structure provides an enclosed container for storing a supply of duplicating bands and spare parts for repair purposes.

The frame member 10 journals a crank arm 26 90 provided with handle 27 and having a pinion 28, Figure 4, for meshing with means to be subsequently described for the purpose of imparting rotary movement to the cylinder.

The frame forms a support for a plurality of 95 paper trays one being positioned below the printing cylinder for supporting the work sheets to be duplicated and the other being positioned to the side of the cylinder for receiving the duplicated sheets. The paper supporting tray 30 is pivotally mounted in the frames 10 and 11 by means of a yoke member 31 having its arms pivotally secured to the frames by pivot pins 32. The tray is provided with upstanding side flanges 33 terminating short of the upper end of the tray 100 and with an adjustable rear flange 34 adjustably positioned through actuation of the set screw 35. Also supported from the spaced frame members is a receiving tray 36 having marginal flanges 37 and being pivotally secured to the frames at its 110

inner end by means of a supporting yoke 38 and securing members 39. The pivotal construction permits the tray to be dropped to assume inoperative position, the arms 40 pivotally secured 5 to the tray at an intermediate point serving to releasably maintain the tray in an elevated or operative position. For the purpose the arms are provided at their lower ends with a notch 41 having engagement with set screws 42 located in the 10 respective frame members.

Referring more particularly to Figures 2 and 3 the duplicating cylinder is shown as comprising spaced end members 44 and 45 provided with inwardly directed peripheral flanges 46 and being 15 mounted in spaced relation adjacent the respective frame members on a transverse operating shaft 47 suitably journaled in the members. A left hand hub member 48 is mounted on shaft 47 and provides securing bolts 49 by means of 20 which the end member 45, the gear 50 and the cam 51 is secured to the hub and thus to the shaft. As the diameter of the gear 50 is substantially the same as that of the end member additional securing means are provided in bolts 25 52 which also hold the cam 51 in position spaced a slight distance from the gear. Similar structure including a hub member 53 providing securing bolts 54 serves to secure to shaft 47 the end frame 44 and also the gear 55 which is spaced 30 outwardly from the end member by washers 56 so as to have meshing engagement with the pinion 28 forming part of the manual operating means. By the above it will be clearly seen that the end members forming a part of the duplicating 35 surface to be more particularly described are mounted for rotation within the frame members, the rotation being imparted manually by rotating pinion 28 through actuation of the crank handle 26. The invention contemplates an alternative structure wherein the shaft 47 is fixedly 40 mounted within the frame members and the hubs 48 and 53 are rotatably mounted thereon.

The cylinder is completed by associating with the end members an arcuate platen 58 suitably secured at its ends to the marginal flanges 46 and extending for substantially half the circumference of the cylinder providing the printing surface of the same. The platen 58 is formed with inwardly bent terminal portions 59, one of 50 which has secured thereto a plurality of spaced pins 60 serving to detachably secure to the portion 59 one end of a gelatin band 61 which is stretched over and supported on the surface of the platen to form a duplicating surface, the other end being detachably secured to shaft 62 provided with projecting pins 63 and being journaled in the respective end members 44 and 45. In order to hold the band in stretched position on the platen shaft 62 is provided with a ratchet 55 wheel 64 adapted to have engagement with the locking pawl 65 pivoted to the end member 44 and having an outwardly projecting stud 66 secured to its other end and extending through the arcuate slot 67. To the right end of shaft 62 is secured a knurled operating wheel 68 providing accessible means for the operator so that the shaft can be rotated for releasing the gelatin band or for stretching the band over the platen 60 48 in which case the shaft is held in position by the locking pawl 65.

A feature of the invention is the particular mounting and actuation of the paper supporting plate 30 which is operated in a manner to contact the top sheet of the stock on the tray with the 65 gelatin band 61 to initiate the duplicating opera-

tion. Pivotally secured by means of the stud 70 to the side frame 11 is an actuating lever 71 having a roller 72 suitably secured to its upper end for engaging with the cam 51 and having a forwardly extending arm 73 integral therewith at its lower end for pivotal connection at 74 to an arm of the yoke 31. It will be noted that the lever 71 has connection with the supporting means for the tray at a point below and immediately adjacent the pivoting studs for the tray and as these are positioned below the center of the same a small movement of lever 71 will result in materially greater movement of the upper end of the tray adjacent the rotating cylinder. For adhering the work sheets to the gelatin band 61 all that is necessary is to cause engagement between the sheet and the band, the same being only momentary, since the adherent nature of the band is sufficient to readily cause the sheet to adhere thereto. For actuating the tray to accomplish the above the cam 51 has a substantially cylindrical periphery with the exception of a dip 75, the same having a position on the cam relative to the leading edge of the gelatin band such as to oscillate or rock the tray through actuation of lever 71 at that point in the rotation 100 of the cylinder to contact the upper marginal edge of the sheet with the leading portion of the duplicating surface.

Since the tray is in position as shown in Figure 4 to contact the sheet with the gelatin band for a 105 relatively short interval of time it will be understood that the oscillating movement imparted to the tray must be relatively rapid. No interference to the rotation of the cylinder results and the feeding operation is of a character to present the 110 sheet to the duplicating surface so that the leading marginal edge of the sheet overlaps the secured end of the gelatin band for purposes which will be clearly understood when the stripping mechanism is described.

Having contact with the duplicating band carried by the cylinder is an impression roller 76 mounted on a transverse shaft 77 suitably journaled in supporting arms 78. The arms are pivoted to the respective frame members by studs 120 80 and have secured to their rear ends the coil springs 81 depending from the studs 82 projecting from the frames. By pivoting the arms supporting the impression roller the same is mounted for movement with respect to the cylinder and as the 125 coil spring 81 yieldingly forces the same into contact with the gelatin band the same operates to impress the fed sheet upon the surface of the band, maintaining uniform the pressure exerted thereon. For stripping the duplicated sheet from 130 the surface of the gelatin band a pair of stripping rollers 84 and 85 are provided, the former being mounted on shaft 86 journaled in the frame members of the machine while roller 85 is suitably mounted on shaft 87 journaled in pivotally 135 mounted arms 88. An arm is pivotally secured by stud 90 to each side frame and has suitably secured to its rearwardly projecting end a coil spring 91, the other end of which is secured to the stud 92. The pivotal arms position the roller 85 140 adjacent the roller 84 and through the tension exerted by the coil spring 91 the former roller is yieldingly urged into contact therewith. Gear 50 as shown in Figures 1 and 2 has meshing engagement with pinion 93 mounted on stud 94 secured 145 to the side frame 11, the pinion in turn meshing with pinion 95 mounted on shaft 86. The roller 84 is therefore driven by the rotating cylinder and roller 85 is likewise driven from the cylinder since the same contacts roller 84. The stripping 150

rollers have rotation in that direction to strip the duplicated sheet from the surface and feed the same to the receiving tray 36.

The invention contemplates novel means for positively presenting to the rollers the leading edge of the duplicated sheet. Pivotally mounted in the frame member 10 by means of stud 92 is an arm 96 to which is suitably secured one end of a yoke member 98, the same extending parallel to 10 and being adapted to co-operate with the stripping rollers 84 and 85. The other end of the member is suitably secured to arm 100 pivotally mounted in frame member 11 by stud 92. Arm 100 is considerably longer than arm 96 and is 15 provided on its projecting end with roller 101 for co-operating with the cam members 102 and 103 suitably secured to the coil spring 105, each spring being in turn secured to stud 106 projecting from each frame member of the machine.

20 For operating the rotary duplicator constructed as above described paper stock of the required length is placed in the tray and by rotation of the crank handle 26 rotary movement is imparted to the cylinder while the tray 30 pivotally mounted 25 in the frame members of the machine is oscillated in timed relation therewith to contact the top sheet of the paper stock with the leading edge of the duplicating surface. The actuation of the tray is so timed as to cause the sheet to adhere to 30 the surface, the registration of the same thereon providing a projecting end which facilitates in the stripping of the duplicated sheet. Continued rotation of the cylinder serves to locate the fed sheet between the surface and the impression 35 roller 76, whereupon the sheet is impressed upon the duplicated surface to perform the duplicating operation. At this point in the rotation of the cylinder the roller 101 on arm 100 is engaged by cam member 102, further rotation actuating the 40 arm and thus the member 98 to locate the same in its lowermost position where the member is spaced a considerable distance from the stripping 45 rollers such as shown in Figure 5.

It will be observed that the member 98 is positioned to the right of the projecting end of the duplicated sheet and upon further rotation of the cylinder it will be seen that the projecting end of the sheet and the member 98 travel upwardly at substantially the same rate, the member moving 50 out of the path of the terminal portion 59 of the platen 58 and toward the end of the sheet. The direction of movement taken by the member 98 is determined by the particular position of the pivot points 92 which by their relation with respect to 55 the stripping rollers cause the member to engage the projecting end of the duplicated sheet and locate the same between the rollers.

The stripping rollers are continuously rotated and it is only necessary that the leading edge of 60 the sheet be inserted therebetween, whereupon the rollers are operative to strip the sheet from

the duplicating surface and feed the same to the receiving tray 36 as will be clear from an inspection of Figure 6.

It is to be understood that I do not wish to be limited by the exact embodiment of the device shown which is merely by way of illustration and not limitation, as various and other forms of the device will of course be apparent to those skilled in the art without departing from the spirit of the invention or the scope of the claims.

I claim:

1. A rotary duplicator including frame members journaling a duplicating cylinder, a paper tray pivotally mounted in the frame members and having operative connection with means provided on the cylinder, said tray being positioned diagonally in the frame members with its upper end below and adjacent to the cylinder, the tray supporting work sheets to be duplicated with their upper ends adjacent the cylinder, whereby actuation of the tray by rotation of the cylinder will contact the upper end of the top sheet with the duplicating surface.

2. A rotary duplicator, in combination, frame members journaling a cylinder, a printing surface on the cylinder, an impression roller, a pivotally mounted paper tray operating to feed sheets supported thereon to the surface, the feeding operation adhering the sheet in registered position on the surface with its leading end projecting therefrom, a pair of rotating stripping rollers, a pivotally mounted bar normally positioned adjacent the rollers, and means for oscillating the bar to locate the same a distance from the rollers and in the path of the leading edge of the printing surface, said bar being operative upon return movement toward the rollers to direct the projecting end of the sheet between the rollers.

3. A rotary duplicator comprising a frame; a platen mounted on an open sided cylinder journaled in said frame, said platen being provided with a duplicating surface; means for feeding a paper sheet into contact with said duplicating surface; an impression roller mounted for yielding engagement with said duplicating surface so as to impress the sheet thereon; a pair of stripping rollers mounted beyond the impression roller; and guide-means mounted on said frame and adapted to move into the open side of said cylinder and direct the advanced end of said sheet into contact with said stripping rollers, said guide-means having a cam-arm engaging a cam provided on the end of said cylinder.

4. Mechanism as specified in claim 3, in which one of the stripping rollers is provided with a gear which meshes with an idler gear driven by the cylinder and the other stripping roller is journaled in a swinging bracket so as to be yieldingly urged towards the driven roller.
